CLAIM

The ornamental design for an architectural panel with embossed pebble design, as shown and described.

DESCRIPTION

FIG. 1 is a front perspective view of an architectural panel with embossed pebble shown used in a partition structure;

FIG. 2 is an enlarged front perspective view of the central area shown in FIG. 1;

FIG. 3 is a left side sectional view taken along line 3—3 of FIG. 4;

FIG. 4 is a front elevation view;

FIG. 5 is a right side sectional view taken along line 5—5 of FIG. 4;

FIG. 6 is a bottom sectional view taken along line 6—6 of FIG. 4;

FIG. 7 is a top sectional view taken along line 7—7 of FIG. 4; and,

FIG. 8 is a rear elevation view.

The broken lines showing environment in the drawings are included for illustrative purposes only and form no part of the claimed design. The outer broken line boundaries in Figures depicting the boundaries of the claimed design indicate that a specific length, width, and thickness form no part of the claimed design and are for illustrative purposes only.

The claimed architectural panel with embossed pebble design includes a transparent or transparent resin or glass sheet with pebble-shaped recesses extending into a surface thereof. The resin or glass sheet of the claimed architectural panel with embossed pebble design can optionally be colored, such as by one or more colored films bonded to the surface opposite the surface with the pebble-shaped recesses. The claimed architectural panel with embossed pebble design can be used as a part of a ceiling, wall, partition, floor, or other architectural structure.
